UNITED STATES PATENT OFFICE.

MASAHIKI NAKATA, OF CRYSTALSPRINGS, WASHINGTON.

ROTARY FAN.

1,167,711.

Specification of Letters Patent.

Patented Jan. 11, 1916.

Application filed April 17, 1915. Serial No. 21,942.

To all whom it may concern:

Be it known that I, MASAHIKI NAKATA, a subject of the Emperor of Japan, residing at Crystalsprings, in the county of Kitsap 5 and State of Washington, have invented a certain new and useful Improvement in Rotary Fans, of which the following is a specification.

My invention relates to improvements in 10 rotary fans, and the object of my invention is to provide a rotary fan which embodies a plurality of blades and a hub portion to which said blades are attached by means which will maintain them in their relative 15 operative positions while such fan is in a condition for practical operation, but which means will permit said blades to be folded compactly together to occupy little space when it is desired to place such fan in a 20 receptacle, as one's pocket or as one's handbag, to carry it from place to place, and which fan shall be adapted easily to be attached and detached, as desired, to a projecting end of the shaft of a motor mechanism, as for instance, to the end of the 25 driven shaft of a hand operated motor mechanism similar to that shown and described in my co-pending application Serial No. 1,533, filed Jan. 11, 1915, for Letters 30 Patent for a vibrator, whereby such mechanism may be operated by the power of one hand of the operator while his other hand disposes the structure to cause such fan to direct a current of air in any desired direction. 35 I accomplish this object by devices illustrated in the accompanying drawings wherein—

Figure 1 is a view in side elevation of the 40 end portion of a fragment of a shaft which may be rotated by suitable motor mechanism, not shown, upon which end portion is mounted a fan embodying my invention which fan is shown in vertical section on broken line x, x of Fig. 2; Fig. 2 is a view 45 in front elevation of said fan as it appears when detached from a shaft; Fig. 3 is a view of the same in front elevation as it appears when its blades are folded compactly together; and Fig. 4 is a sectional view of parts of the same on broken line y, y of Fig. 2.

Referring to the drawings, throughout 50 which like reference numerals indicate like

parts, 5 is a hub portion, preferably made of sheet metal, of a form somewhat resembling a triangle and provided with an oblong hole 20 through its central portion to adapt it to be secured in a fixed circumferential position on a shaft provided with opposite flattened surfaces.

A fan blade 6 of slightly flexible sheet metal material, as springy sheet metal or as sheet celluloid, is securely riveted by rivets 9 and 10 to one corner portion 11 of the hub 5 while like fan blades 7 and 8 are pivotally 65 attached respectively to corner portions 12 and 13 by pivot rivets 14 and 15, respectively, whereby said blades 7 and 8 may be swung to the respective positions as shown in Fig. 3.

Near the outer end of each of the corner portions 12 and 13 is fixed a dowel pin (as dowel pins 16 and 17 respectively) which projects from the front surface thereof for a distance about equal to the thickness of 70 said fan blades 6, 7 and 8, and the fan blades 7 and 8 are each provided with a hole, as holes 18 and 19, of a size to permit the respective one of the dowel pins 16 and 17 to enter thereinto, as indicated more clearly 75 in Fig. 4, when said fan blades 7 and 8 are moved to their positions as shown in Fig. 2. To move said fan blades 7 and 8 between their positions, as shown in Fig. 2, and their 80 positions as shown in Fig. 3, they are 85 pressed by one's hand to cause them to yieldingly move forward a sufficient distance to permit their rear surfaces to swing free from engagement with the top of said dowel pins 16 and 17, but when released 90 from one's hand at the positions shown in Fig. 3 then, by reason of their springy material, they will spring back to cause said dowel pins 16 and 17 to project into their respective holes 18 and 19 thus to maintain 95 them in their operative positions.

In Fig. 1, 21 is the end portion of a fragment of a shaft which is provided with a collar 22 fixed securely thereon, said shaft 21 terminating with a screw-threaded portion 23 upon which is removably disposed a milled nut 24.

A portion of the collar 22, adjacent to the screw-threaded portion 23, is flattened on opposite sides to have a cross-section cor- 105 responding to the shape of the hole 20 in the

hub 5 of the fan and upon such portion of said collar 22 is disposed said hub 5 of the fan, where it is securely fastened by pressure of the milled nut 24 in an obvious manner.

The several blades 6, 7 and 8 are symmetrically disposed each with its plane at a slight angle with respect to the plane of the hub 5, whereby, when rotated, they may act 10 in a well known manner to create a current of air, and the direction of rotation, as indicated by the arrows, should be such as will tend to cause them to be pressed back against the front surfaces of the corner portions 11, 12 and 13 of the hub 5.

Manifestly a fan may have more than three fan blades or only two, and the form and dimensions of parts of my invention

may be changed without departing from the spirit thereof.

20

What I claim is:

A rotary fan comprising a polygonal hub, a pivot located in each angle of said hub between the apex of the angle and the center of the hub, a stop pin located adjacent the apex of each angle, and blades each having an end carried by said pivot and provided with openings registerable with said stop pin.

25

In witness whereof I, hereunto subscribe my name this third day of April, A. D., 1915.

MASAHACHI NAKATA.

Witnesses:

FRANK WARREN,
O. JOHNSON.
